Primary Examiner — Catherine Ho

(57) **CLAIM**

The ornamental design for a sign as shown and described.

DESCRIPTION

FIG. 1 is a bottom rear side perspective view of a sign showing my new design;

FIG. 2 is a rear view of the sign;

FIG. 3 is a front view of the sign;

FIG. 4 is a left side view of the sign;

FIG. 5 is a right side view of the sign;

FIG. 6 is a top view of the sign; and,

FIG. 7 is a bottom view of the sign.

The broken lines illustrate portions of the sign that form no part of the claimed design.
